UNITED STATES PATENT OFFICE

115,545

DESIGN FOR A FLY BOX

William J. De Witt, Auburn, N. Y., assignor to Shoe Form Co., Inc., Auburn, N. Y., a corporation of New York

Application August 27, 1938, Serial No. 79,602

Term of patent 14 years

To all whom it may concern:

Be it known that I, William J. De Witt, a citizen of the United States of America, residing at Auburn, in the county of Cayuga and State of New York, have invented a new, original, and ornamental Design for a Fly Box, of which the following is a specification, reference being had to the accompanying drawing, forming a part thereof.

Fig. 1 is a perspective view of a fly box showing my new design; and

Fig. 2 is a front elevation thereof.

The appearance of the opposite side of the box is substantially the same as that of the side shown.

I claim:

The ornamental design for a fly box, substantially as shown and described.

WILLIAM J. DE WITT.
